CLAIM

The ornamental design for a front cap for vehicle, as shown and described.

DESCRIPTION

FIG. 1 is a front-right perspective view of a front cap for vehicle showing our new design;

FIG. 2 is a front view thereof;

FIG. 3 is a left side view thereof;

FIG. 4 is a right side view thereof; and,

FIG. 5 is a top view thereof.

The broken lines in FIGS. 1 and 5 show portions of the front cap for vehicle that form no part of the claimed design.
